COOLING SYSTEM OF INTERNAL COMBUSTION ENGINES

Application filed October 3, 1929, Serial No. 397,083, and in Great Britain November 29, 1928.

This invention relates to the cooling systems of internal combustion engines in which the steam formed is condensed in a surface condenser, and the condensate returned to the cylinder jacket. In such systems it has been proposed that the water (or other liquid) in the jacket should be maintained at or near its boiling point. For the sake of convenience, the cooling medium will be referred to as water.

According to the present invention the outlet or outlets from the water jacket or jackets in the cooling system of an internal combustion engine is or are restricted so that the pressure in said jacket or jackets may be maintained high enough to prevent boiling therein, the pressure in the system beyond said restricted outlet or outlets being lower until the water (including the condensate) is to be returned to the jacket or jackets.

Preferably the pressure in the system is still further reduced just in advance of the junction therewith of the passage for the return to the system of the condensate.

Preferably also the pressure in the system is raised again between said junction and a pump of any convenient type by which the water is returned to the water jacket or jackets, the connection between said junction and pump being smooth internally so as to avoid any eddy currents.

The invention is to be applied, primarily, to the cooling system of the internal combustion engine of an aircraft and, for the sake of convenience, will be described with reference thereto in connection with the accompanying drawings wherein Figure 1 is a diagrammatic side view and Figure 2 is a diagrammatic front view of one form of the invention.

As shown water is pumped into the water jacket *a* of an engine *b* the outlet passages *c* from said jacket *a* being restricted as at *d* so that the pressure created in said jacket can be maintained high enough to prevent boiling of the water therein and keep said jacket filled with water under all conditions. Beyond said constricted outlets *d* the passages *e* of the system are enlarged so that the pressure is reduced and steam is formed. The

mixture of steam and water is led tangentially into a centrifugal separator *e*, whence the separated water is led off by one pipe *f* and the vapour by another *g*. The vapour is conducted into a domed chamber *h*, whence it escapes, more or less freed from liquid spray, by a pipe *j* opening from the top of the dome and leading to a surface radiator *k*, (which may form any part of the surface of the aircraft which is exposed to free air) whilst free water which may have been carried along with the vapour settles at the bottom of the domed chamber *h* and is conducted away by a drain pipe *m* branching into the outlet pipe *n* which conveys away the condensate from the radiator *k*. The radiator *k* might also be termed a condenser. It functions at one and the same time both as a radiator and as a condenser during the normal operation of the engine. It serves to condense steam separated from the cooling water, and it is then functioning as a condenser. It also serves, at the same time, to radiate heat abstracted from the engine, and it then functions as a radiator, serving to cool the water circulated in the jacket of the engine by radiating the heat given to it by the condensing steam.

When the system is first charged with water at atmospheric temperature the domed chamber *h* is left empty, but the expansion of the water when the engine is "warmed up," causes an overflow into said chamber. In order to maintain the reserve of water so created by expansion the drain pipe *m* is of such size that the quantity of water which can flow therethrough is equal approximately to the quantity of free water which will be carried along with the vapour coming from the centrifugal separator *e*. When the engine is stopped and the water in the system contracts on cooling the chamber *h* empties and restores the level of water in the main portion of the circuit. The outlet pipe *n* which conveys away the condensate from the radiator *k* is joined with the water pipe *f* from the centrifugal separator *e* and in order to allow an adequate head for the entry of the condensate into the water pipe *f*, the latter is tapered to a smaller section or

throat as at σ so as artificially to reduce the pressure therein and it is enlarged again beyond said throat so as artificially to increase the pressure therein at the inlet p to the pump q , in order to avoid boiling at said inlet, care being taken that the interior of said enlarged portion is smooth internally.

At the outlet end of the radiator k is provided a double relief valve r , of known kind, adapted to open at predetermined maximum 10 and minimum pressures, to maintain the pressure at that part of the system, within a desired range relatively to the atmosphere, whilst an emergency valve s is provided at the top of the centrifugal separator e to limit 15 the pressure in the system to the maximum safe pressure for the vapour passages and radiator. Satisfactory operation of the system in the engine cooling passages may be indicated by one or more suitably disposed 20 and connected fluid-pressure gauges such as t .

The provision of restricted outlets d from the water jacket a in accordance with this invention presents that resistance to the flow of water under the action of the pump q 25 which is necessary to create and maintain a pressure such that the water will not boil in said jacket whilst the condensation of steam which, in effect, is the cooling effected by the system, may be carried out in parts which do 30 not have to withstand a high pressure and consequently can be made lighter than would be possible if the pressure throughout the system were practically constant.

35 We claim:—

1. In a cooling system for an internal combustion engine, a water jacket, a centrifugal separator positioned above said water jacket, pipes leading from said water jacket to said 40 separator, said pipes having restricted portions directly adjacent said water jacket, a domed chamber above said water jacket, a vapor pipe connecting said separator and said domed chamber, a condenser connected to said domed chamber, a water pump for said water jacket, and water pipes leading from said separator and from 45 said condenser to said pump, said pipes meeting before reaching said pump and having a 50 restricted throat near said pump.

2. In a cooling system for an internal combustion engine, a water jacket, a centrifugal separator positioned above said water jacket, pipes leading from said water jacket to said 55 separator, said pipes having restricted portions directly adjacent said water jacket, a domed chamber above said water jacket, a vapor pipe connecting said separator and said domed chamber, a condenser connected 60 to said domed chamber, a water pump for said water jacket, and water pipes leading from said separator and from said condenser to said pump, said pipes meeting before reaching said pump and having a restricted 65 throat near said pump, the inlet to said pump

having a smooth surfaced interior to prevent eddy currents.

3. The method of operating a liquid cooling circuit of an internal combustion engine comprising a heat absorbing section and a 70 heat dissipating section, which consists of maintaining pressure within the heat absorbing section to prevent boiling of the liquid therein, separating the vapor from the liquid as the vapor is passed to the heat dissipating section, returning the vapor in condensed form to said heat absorbing section by means of a pump, and increasing the pressure of said condensed vapor directly before it reaches the pump. 80
